(57) CLAIM

The ornamental design for an inflatable float, as shown and described.

DESCRIPTION

FIG. 1 is a perspective view of the inflatable float showing my new design;

FIG. 2 is a left side elevation of the inflatable float, the right side elevation is a mirror image thereto;

FIG. 3 is a top plan view thereof;

FIG. 4 is a bottom plan view thereof;

FIG. 5 is a front elevational view thereof; and,

FIG. 6 is a rear elevational view thereof.
